UNITED STATES PATENT OFFICE.

ROBERT TODD LOWD, OF CHATTANOOGA, TENNESSEE.

PEDAL.

1,070,971.

Specification of Letters Patent.

Patented Aug. 19, 1913.

Application filed July 17, 1912. Serial No. 710,050.

To all whom it may concern:

Be it known that I, ROBERT T. LOWD, citizen of the United States, residing at Chattanooga, in the county of Hamilton and State of Tennessee, have invented certain new and useful Improvements in Pedals, of which the following is a specification.

This invention relates to pedals and more particularly to a pedal designed especially for use on motor-cycles.

One aim of the invention is to provide a pedal of this class which, while it does not embody ball or roller bearings will nevertheless rotate freely upon its spindle and with but little friction.

Another aim of the invention is to provide a pedal the hub of which will not be liable to become filled with dust and dirt and which may be readily and quickly detached from and applied to its spindle without the use of tools.

A further aim of the invention is to provide means for holding the pedal upon its spindle, which means will insure against accidental removal of the pedal, although it may be readily and quickly manipulated to provide for release of the pedal.

For a full understanding of the invention reference is to be had to the following description and accompanying drawing, in which:—

Figure 1 is a vertical longitudinal sectional view through the pedal embodying the present invention, parts being shown in plan. Fig. 2 is a vertical transverse sectional view on the line 2—2 of Fig. 1. Fig. 3 is a perspective view of the spindle on which the pedal is mounted. Fig. 4 is a group perspective view illustrating the device employed for holding the pedal in place upon its spindle.

Corresponding and like parts are referred to in the following description and indicated in all the views of the accompanying drawing by the same reference characters.

In the drawing, the spindle upon which the pedal is mounted is indicated by the numeral 1 and is formed adjacent one end with the usual head 2 having flattened sides 3 for the engagement of a suitable wrench, whereby its threaded end 4 may be screwed into or unscrewed from the usual opening in the pedal crank. The spindle 1 is reduced from about a point midway between its ends to its end opposite its threaded end

4 as indicated at 5 and, for a purpose to be presently explained, is formed at the inner end of its reduced portion with a conical portion 6 which merges into the surfaces of the body and reduced portion of the spindle. It will also be noted that the extremity of the reduced portion of the spindle is rounded as at 7. Also for a purpose to be presently explained the spindle 1 is formed between its head 2 and the conical portion 6 with a circumscribing groove 8, the formation of which results in a shoulder 9 extending entirely around the spindle 1.

The hub of the pedal is in the form of a sleeve 10 into the outer end of which is fitted the neck 11 of a hub cap 12. The neck 11 is cylindrical and is formed with a bore 13 which is arranged to receive the end of the reduced portion 5 of the spindle, in a manner illustrated in Fig. 1 of the drawing. The hub cap 12 is formed with a circumscribing shoulder 14. Fitted into the other end of the sleeve 10 is the neck 15 of a cap 16 which is also formed with a circumscribing shoulder indicated at 17. The cap 16 is hollow and is interiorly cylindrical in form and at its outer end is increased in diameter as at 18. By enlarging the head as at 18, a shoulder 19 is formed. Fitted onto the head 12 is a tread supporting plate 20, and a similar plate 21 is fitted onto the head 16, these plates being disposed against the shoulders 14 and 17 respectively. The treads which are supported by the plate are indicated by the numeral 22 and they are mounted in place upon bolts 23 extending between the plates. The formation of the head 2 results in a shoulder 24 which opposes the shoulder 19 when the spindle is fitted within the hub and disposed between these shoulders 19 and 24 is a fiber washer 25 which constitutes a wear preventing means as well as a means for preventing the entrance of dust and grit into the hub.

As before stated, means is provided for detachably holding the hub 10 upon its spindle 1, and this means consists in part of a leaf-spring 26 which is secured at one end by means of a screw 27 to the sleeve 10 and has its free end projecting in the direction of the head 16 but terminating short thereof. At its free end the spring 26 carries a lug 28 which has a plane face 29 presented in the direction of the outer end of the hub and its rounded or beveled face 30 presented in the opposite direction. This lug is

normally held by the resiliency of the spring 26 to project through an opening 31 formed in the wall of the sleeve 10.

In assembling the parts, the hub 10 is slipped onto the spindle 1 and as the spindle enters the hub its conical portion 6 will ride beneath the beveled face of the lug 28 and the lug will be lifted and held lifted by the body portion of the spindle until the spindle has been inserted so far as to bring its groove 8 into registration with the opening 31, whereupon the lug will be snapped into the groove with its plane face 29 engaging against the shoulder 9. At such time the rounded end of the spindle portion 5 will be received in the neck 11 and the shoulders 19 and 24 will bear against opposite sides of the washer 25.

From the foregoing it will be readily understood that the pedal is securely held against accidental removal from its spindle after having been applied thereto, by the engagement of the lug 28 in the groove 8 of the spindle, but that it may be readily removed if desired by lifting up the free end of the spring 26 so as to disengage the said lug from the groove.

It will be apparent from the foregoing that not only does the groove 8 of the spindle 1 serve to receive the engaging end of the lug upon the spindle but that the formation of this groove serves to weaken the spindle at this point so that should the outer side of the pedal strike the road surface turning a corner, the spindle will snap at this weakened portion and bending or breaking of the pedal crank will be prevented.

Having thus described the invention what is claimed as new is:—

1. In a pedal, a spindle, a hub removably and rotatably fitted thereon, and means upon the hub yieldably held in coöperative relation to the spindle whereby to hold the former in place upon the latter.

2. In a pedal, a spindle, the said spindle being formed with a circumscribing groove, a hub removably and rotatably fitted upon the spindle, and means upon the hub projecting into the groove and arranged to hold the hub upon the spindle.

3. In a pedal, a spindle, formed with a circumscribing shoulder, a hub removably and rotatably fitted upon the spindle, and means upon the hub yieldably held in engagement with the shoulder whereby to hold the hub in place upon the spindle.

4. In a pedal, a spindle formed with a circumscribing groove and with a tapered portion, and a device carried by the hub and yieldably held in position to ride upon the

tapered portion of the spindle and engage in the groove therein when the hub is fitted onto the spindle, the engagement of the device in the groove serving to hold the hub 65 upon the spindle.

5. In a pedal, a spindle, the said spindle being provided with a circumscribing groove, a hub removably and rotatably fitted upon the spindle and having an opening in its wall, and a spring-pressed lug carried by the hub and yieldably held to project through the opening in the hub and into the groove in the spindle.

6. In a pedal, a spindle having a circumscribing shoulder, a hub rotatably and removably fitted upon the spindle and formed with an opening arranged to register with the shoulder upon the spindle when the hub is in place upon the spindle, a leaf-spring 80 secured to the hub, and a lug carried by the leaf-spring and yieldably held thereby to project through the opening in the hub and into engagement against the said shoulder.

7. In a pedal, a spindle formed with a circumscribing groove, the said spindle having a tapered portion, a hub removably and rotatably fitted upon the spindle and formed with an opening arranged to register with the groove when the hub is in place upon the spindle, a leaf-spring secured upon the hub, and a lug carried by the free end of the leaf-spring and normally held to project through the opening in the hub and into the groove in the spindle and having a plane 95 face arranged to abut against one wall of the groove, and a bevel face arranged to ride over the tapered portion of the spindle when the spindle is inserted into the hub.

8. In a pedal, a spindle, having a shoulder located adjacent its inner end, a hub removably and rotatably fitted upon the spindle and having a shoulder arranged to oppose the shoulder upon the spindle, and a washer fitted upon the spindle and confined between 105 the said shoulders.

9. In a pedal, a spindle having a shoulder located adjacent its inner end, a hub comprising a sleeve, a hollow cap fitted in one end of the sleeve and having a shoulder opposing the shoulder upon the spindle, a washer disposed between the said shoulders, and a cap fitted in the other end of the sleeve, and having a bore receiving the outer end of the spindle.

In testimony whereof I affix my signature in presence of two witnesses.

ROBERT TODD LOWD.
